UNITED STATES PATENT OFFICE.

FRANK I. JOYCE, OF DAYTON, OHIO.

DESIGN FOR A LIFTING-JACK STAND.

SPECIFICATION forming part of Design No. 30,199, dated February 14, 1899.

Application filed January 21, 1898. Serial No. 667,653. Term of patent 14 years.

To all whom it may concern:

Be it known that I, FRANK I. JOYCE, a citizen of the United States, residing at Dayton, in the county of Montgomery and State of 5 Ohio, have invented and produced a new and useful Design in Lifting - Jack Stands, of which the following is a specification.

Figure 1 is a perspective view of a lifting-jack stand. Fig. 2 is a similar view showing 10 the opposite side thereof. Fig. 3 is a cross-section of the upper portion thereof, taken through the circular body.

The leading features of my design are, first, a standard composed of a column which is substantially rectangular in cross-section at top 15 and bottom and is connected at the bottom to a substantially flat base, a series of connecting-ribs joining the column at right angles, one at each side, which are also joined to the base, and, second, in the circular body which is supported by the standard and projects from one side thereof, said body consisting of a large circular chamber and a small circular chamber concentrically arranged with reference 20 to the large chamber and at one side thereof and opening thereinto.

Referring to the accompanying drawings, *a* indicates the column of the standard, *b* the base thereof.

25 *c* indicates the ribs, which are arranged at right angles to the different sides of the column *a* and connected to it and to the base *b*.

d indicates the large chamber of the body, which, as shown in Figs. 2 and 3, is attached to the standard *a* at one side, near the upper 35 end thereof.

e indicates the small chamber, which, as shown in Figs. 2 and 3, is arranged concentrically with the large chamber and adjacent to the column *a*.

f indicates a portion of one side of the column *a*, which forms a part of the inner wall of the large chamber *d*. The chambers *e* and *d* communicate, however, as shown in Fig. 3, as the part *f* does not separate them. The 45 front wall or cover *g* of the large chamber *d* and the opposite wall *h* of the small chamber *e* are provided with alined openings *k l*, respectively, as shown in Fig. 3.

m n indicate ribs which project from one 50 side of the body of the standard and are parallel with each other, as shown in Fig. 1, said ribs forming continuations of the ribs *c c*, as shown. The ribs *m n* are provided with perforations *o p*.

Having thus described my invention, what I claim is—

The design for a lifting-jack stand, substantially as shown and described.

FRANK I. JOYCE.
